UNITED STATES PATENT OFFICE.

THOMAS R. COOK, OF SCRANTON, PENNSYLVANIA.

CAR UNDERFRAME.

Application filed December 23, 1926. Serial No. 156,654.

The invention relates to a car underframe of substantially the full length of the car of which it is to form a part, and such invention has reference to a cast metal frame 5 of this character designed primarily for a mine or analogous car.

One object of the invention is to provide a one-piece car-length underframe whose least protected portions are weaker than its 10 major portion for the purpose of localizing injury to the frame in case said portions should strike or be struck by objects which would otherwise more seriously injure the frame and car. The relatively weak portions, by yielding or possibly crushing under 15 impact, will relieve the remainder of the frame and car from such strain and shock as would in all probability do serious damage thereto.

20 A further object of the invention is to provide an underframe which may be readily cast and removed from the flask in which it is so formed, by a single parting of said flask.

25 Yet another aim is to provide a frame of such form that a number of the openings necessary for the attachment of car parts may be formed by cores during the casting operation, while the remaining openings 30 may be drilled with the aid of a template at a single setting of the frame in a drilling machine.

35 A still further aim is to provide a frame which may be easily and rather inexpensively manufactured, yet will be efficient and durable and will readily permit detachment of car parts for repair or replacement.

With the foregoing in view, the invention resides in the novel subject matter herein- 40 after described and claimed, the description being supplemented by the accompanying drawings.

Fig. 1 is a top plan view of an underframe constructed in accordance with the invention.

Fig. 2 is an end view.

Fig. 3 is a side elevation.

45 Figs. 4 and 5 are respectively longitudinal and transverse sectional views as indicated by lines 4-4 and 5-5 of Fig. 1.

In the drawings above briefly described, a car-length, cast-metal underframe is shown and a number of the car parts such as the body, wheels, axles, journal boxes 55 and draft gears, are illustrated in dotted lines.

The frame embodies two inner, closely spaced, longitudinal members 6, two relatively heavy, outer, longitudinal members 7 which are laterally spaced from the members 6 and are provided with narrowed end portions 8, and various transverse members connecting said longitudinal members 6 and 7.

Four of the transverse members are indicated by the reference characters 9, two 65 of these members being disposed near each end of the frame. These members 9 converge toward the ends of the frame and have their inner ends joined to the end portions of the members 6, while their outer 70 ends are joined to the relatively heavy body portions of the side member 7, at the juncture of said portions with the narrowed end portions 8. These transverse members 9 are of heavier construction than the nar- 75 rowed end portions 8 but need not be as heavy as the body portions of the side members 7. End members 10 extend from the ends of the members 6 to the outer extremities of the narrowed end portions 8 of the 80 side members 7, and said end members preferably recede somewhat from their inner toward their outer ends.

Short transverse members 11 connect the longitudinal members 6 with each other, 85 near the ends of these members, leaving pockets P between said ends for the reception of the draft gears G. Portions of these draft gears preferably pass slidably through 90 openings in transverse plates 12 having laterally turned ends 13 secured by bolts 14 to the ends of the members 6, said plates serving as additional connecting means for 95 said members, as well as assisting in properly mounting the draft gears.

Additional transverse members 15 connect the central portions of the members 6 with each other, and still other transverse members 16 connect said portions of the members 6 with the corresponding portions 100 of the side members 7. These members 16 may well be provided with lugs 17 upon which parts of the brake rigging may be hung.

Each of the members 6, 7, 9, 10, 11, 15 105 and 16, embodies a flat, plate-like, top portion 18 and a flange portion 19 extending longitudinally thereof and projecting downwardly therefrom. All of the plate-like portions 18 are integrally joined to each other 110 and they are disposed in a common horizontal plane, and all of the flange portions 19

are free of lateral projections, are tapered downwardly, and have free lower edges. This construction permits the molded frame to be readily withdrawn from the sand 5 mold in which it has been cast, with only a single parting of the flask, the parting line being flush with the top surface of the portions 18.

Pedestal jaws 20 are formed integrally 10 with and project downwardly from the side members 7 to straddle the usual journal boxes B, said pedestal jaws being downwardly tapered to permit easy removal from the sand mold in which the frame is cast. 15 The flanges 19 of the side members 7, which flanges are located at the inner and outer edges of the plate-like top portion 18 of said side members, preferably have widened ends 21 which are integrally joined to the 20 pedestal jaws 20 to effectively reinforce and brace them. Wear plates 22 are preferably secured by rivets or the like to the inner sides of these pedestal jaws and may be removed and replaced when they have become 25 badly worn. It will be observed that these plates normally protect the pedestal jaws against wear and hence add materially to the life of the frame.

To assist in properly holding the upper 30 ends of the usual springs S in place, bosses 23 are formed on the lower sides of the members 7, between the pedestal jaws 20, these bosses being downwardly tapered for easy removal from the sand.

35 All openings 24 necessary in vertical portions of the frame, for the attachment of car parts, may be formed by cores during the casting of the frame, but all openings 25 in the horizontal top portion of the frame, 40 are preferably drilled with the aid of a template, at a single setting of the frame in a drilling machine.

By providing the novel construction shown and described, a frame is produced 45 which may be readily cast and withdrawn from the mold at a single parting of the flask, and as the openings 24 may be formed by cores during the molding process, a great many drilling operations are obviated. 50 Moreover, by drilling all of the openings 25 of any frame with a common template, the frames will be readily interchangeable.

The frame is rigid, durable and in every 55 way desirable. The major portion of this frame may be considered as consisting of the inner longitudinal members 6, the relatively heavy major portions of the side members 7, and the transverse members 9, 11, 15 and 16. This major portion of the frame is sufficiently heavy to perform all needs, but it 60 need not be made excessively heavy, as it is protected to a large extent against injury, by the relatively weak end portions 8 of the side members 7, and the end members 10. These frame portions 8-10 are

disposed at the least protected portions of the frame, that is at its corners, and by having said portions weaker than the major portion of the frame, they will yield or crush under impact, in case of collision, 70 wreck or the like, and hence, they will save the major portion of the frame from undue strain and shock which might otherwise seriously injure the same. These corner portions, being comparatively small, 75 may be easily repaired even if they have become badly damaged, but the chances are that no repairs will then be necessary to the major portion of the frame, as the corner portions have received the brunt of the so shock or impact and hence have protected the major portion of the frame against such impact as would otherwise have seriously injured the same. Excellent results are obtainable from the details disclosed, and 80 they are therefore preferably followed. However, within the scope of the invention as claimed, variations may of course be made.

I claim:

1. A one-piece car-length underframe comprising two inner substantially parallel longitudinal members, two outer longitudinal members laterally spaced from said inner members and having narrowed end portions, transverse members extending obliquely from the end portions of the inner members to the outer members and joined to the relatively wide body portions of the latter at their juncture with said narrowed end portions, said transverse members converging toward the ends of the frame, relatively weak end members connecting the ends of said inner members with the outer extremities of said narrowed end portions, and additional transverse members connecting said inner members with each other. 100

2. A one-piece car-length underframe comprising two inner substantially parallel longitudinal members, two outer longitudinal members laterally spaced from said inner members and having narrowed end portions, transverse members extending obliquely from the end portions of the inner members to the outer members and joined to the relatively wide body portions of the latter at their juncture with said narrowed end portions, said transverse members converging toward the ends of the frame, relatively weak end members connecting the ends of said inner members with the outer extremities of said narrowed end portions, and additional transverse members, certain of which connect said inner members with each other at longitudinally spaced points while others connect said inner members with said outer members. 115

3. A car-length cast metal underframe comprising longitudinal and transverse members, each of said members having a flat 120 125 130

- plate-like top portion and a downwardly projecting longitudinal flange portion, the plate-like portions being integrally joined to each other and disposed in a common plane, 5 the flange portions being also integrally joined to each other, said flange portions being free of lateral projections, having free lower edges and being downwardly tapered for the purpose set forth.
- 10 4. A car-length cast metal underframe comprising longitudinal and transverse members, each of said members having a flat plate-like top portion and a downwardly projecting longitudinal flange portion, the plate-like portions being integrally joined to each other and disposed in a common plane, 15 the flange portions being also integrally joined to each other, said flange portions being free of lateral projections, having free lower edges and being downwardly tapered for the purpose set forth.

joined to each other, said flange portions being free of lateral projections, having free lower edges and being downwardly tapered 20 for the purpose set forth, and downwardly tapered pedestal jaws integral with and projecting downwardly from said longitudinal members to straddle journal boxes, the flange portions of said longitudinal members being 25 integral with said pedestal jaws.

5. A structure as specified in claim 5; said plate-like portions having drilled openings and said flange portions having core-formed openings wherever necessary for attachment of car parts to the frame. 30

In testimony whereof I have hereunto affixed my signature.

THOMAS R. COOK.
